UNITED STATES PATENT OFFICE

DELMER C. LEE, OF MAPLEWOOD, MISSOURI, ASSIGNOR TO MISSOURI ROLLING MILL CORPORATION, OF ST. LOUIS, MISSOURI, A CORPORATION OF MISSOURI

WIRE-SECURING MEANS FOR FENCE POSTS

Application filed February 17, 1931. Serial No. 516,412.

The invention relates to structures in which fence wires are secured by means of wire fasteners against posts, the latter being usually of metal.

5 The object of the invention is to provide a new and improved construction in which the wire fasteners are held in operative position due to their own resiliency, the structure being such that each fastener may be snapped 10 into operative position without the aid of special tools.

With the foregoing in view, the invention resides in the novel subject matter herein- 15 after described and claimed, description being accomplished by reference to the accom- 20 panying drawings.

Fig. 1 is a fragmentary perspective view.

Fig. 2 is an enlarged vertical section on line 2-2 of Fig. 1 but showing the clip before 20 its final movement toward operative position.

Fig. 3 is a view similar to Fig. 2, but showing the clip completely in operative position.

Fig. 4 is a horizontal sectional view on line 4-4 of Fig. 3.

25 A metal post 5 is shown of T-shape in transverse section, said post being provided with a plurality of pairs of openings. The upper opening of each pair is denoted at 6 and the lower opening of said pair at 7, and 30 the anchoring clips 8 for the fence wires W, may be engaged with any or all of said pairs of openings. As all of the clips 8 are of the same construction, a description of one will suffice.

35 The clip 8 is formed from a single length of stiff wire whose upper end is bent laterally and downwardly to provide a hook 9 for passage through the upper opening 6. For further reference, the bight portion of the 40 hook is denoted at 10 and its bill at 11.

The intermediate portion of the clip body is bowed outwardly somewhat as denoted at 12, to accommodate the wire W, and the lower end of the clip-forming wire is bent lat- 45 erally to provide a finger 13 for passage

through the lower opening 7. This finger 13 is bent between its ends to provide it with an upward hump or cam 14. The shortest distance between this hump or cam and the 50 bight portion 10 of the hook 9, is less than

the shortest distance between the upper and lower openings 6 and 7, and the hook bill 11 is disposed in widely diverging relation with the vertical or body portion of the clip. Hence, after initially engaging the hook 9 55 with the opening 6, the bight portion 10 will remain in contact with the lower end of said opening 6 and will pivotally support the clip, while swinging the latter to move its finger 13 through the lower opening 7. By the time 60 the clip reaches substantially the position shown in Fig. 2, its movement is arrested by the hump or cam means 14, and it can only be moved past this position by application of force. As the clip is forced to its final opera- 65 tive position, the hump 14 exerts a cam action, thus momentarily expanding the clip and allowing said hump or cam means to snap past the upper end of the opening 7. As soon as the clip has reached its final operative position, its own resiliency again contracts it, with the result that the clip will stay firmly 70 in position even against strong pressure, without the necessity of clinching the finger 13 against the post. Moreover, should it be 75 desired to remove any of the clips, for instance, to change the positions of the wires W or to move the fence, the clips may be quickly and easily removed simply by striking a blow upon the ends of their fingers 13, 80 and may be again used.

The details disclosed have proven to be advantageous from all standpoints and are preferably followed. However, within the scope of the invention as claimed, minor 85 variations may be made. Moreover, while I have used such terms as "upper" and "lower" in explaining the invention, it will be obvious that the clip could be used inverted, horizontal, or in any other position. Hence, such 90 terms as those quoted, are not to be considered as limiting.

I claim:—

1. A wire mounting fence post having an upper and a lower opening whose axes are 95 transverse to the direction in which the wire extends, and a wire-fastening clip having a pivot hook at one end to engage one of said openings, the other end of said clip having cam means adapted to snap through the other 100

opening when the clip is forcibly swung into operative position, said cam means and post being co-operable to momentarily spring the clip from its normal shape when said clip is forced into position and being thereafter co-operable to hold the clip in place.

2. A fence post having an upper and a lower opening, and a wire-fastening clip comprising a substantially vertical stiff wire having one end bent laterally to provide a hook for passage through one of said openings, the other end of said wire being bent laterally to form a finger for passage through the other of said openings, said finger being provided with a hump between its ends, the bill of said hook being in diverging relation with the body of the clip to allow the bight portion of said hook to rest pivotally upon the inner end of said one opening during movement of said finger through said other opening, the shortest distance between said bight portion and said hump being less than the shortest distance between said openings, whereby the clip will momentarily expand and said hump will snap past the inner end of said other opening when forcibly swinging the clip to operative position.

3. A structure as specified in claim 2; said finger having a bend forming said hump.

30 In testimony whereof I affix my signature.
